UNITED STATES PATENT OFFICE.

ARTHUR JOHN HERBERT BURNETT, OF WIMBLEDON PARK, ENGLAND, ASSIGNEE OF
ONE-HALF TO ROBERT GOODSON, OF HOLBORN, LONDON, ENGLAND.

CASH-REGISTER.

1,119,344.

Specification of Letters Patent.

Patented Dec. 1, 1914.

Application filed August 4, 1910. Serial No. 575,434.

To all whom it may concern:

Be it known that I, ARTHUR JOHN HERBERT BURNETT, a subject of the King of Great Britain, residing at 1 Stuart road, 5 Wimbledon Park, in the county of Surrey, England, have invented certain new and useful Improvements in Cash-Registers, of which the following is a specification.

This invention relates to mechanism for 10 use in connection with calculating machines and the like, wherein the performance of the various arithmetical processes is effected from a keyboard by means of a series of keys adapted to impart varying degrees of 15 movement to one or more indicating drums mounted within a casing in such a manner that the result of each calculation can be seen through an aperture or window in the casing of the apparatus.

20 The invention comprises an improved arrangement of "carry on" mechanism for causing the movement of one counting drum to impart a predetermined amount of movement to the next counting drum and from 25 that drum to the succeeding drum and so on throughout the series of drums, the various movements being effected in a positive manner without any possibility of any of the drums occupying a position in which their 30 various indications can become out of alignment with each other or with the inspection aperture in the casing of the apparatus. An important feature of the "carry on" mechanism comprises a fixed cam interposed be- 35 tween each of the various counting drums the said cam being of such a formation as to cause a movably mounted member carried by one drum to engage during a portion of its revolution with the driving wheel con- 40 nected with the succeeding drum and to impart a predetermined amount of movement to the latter whereupon the said member is disengaged by the cam and travels around the same during the remaining por- 45 tion of its revolution without imparting any further motion to the driving wheel.

The invention also comprises a keyboard in which the keys are connected to the driving mechanism for actuating the counting 50 drums through the intervention of a lost motion device by means of which each key receives the same amount of movement in effecting its full stroke, the said lost motion being arranged to come into operation 55 in advance of the effective part of the stroke

whereby in the event of one key receiving a complete stroke while the first mentioned key remains in its partly depressed condition, the amount of movement transmitted to any of the counting drums by the depression of the two keys will be the same as that which would have been transmitted by the first mentioned key if the latter had received a full stroke in the first instance.

60 The invention further comprises improved means for compelling each of the key levers to receive a full stroke before it can again return to its normal or top position, a locking device for preventing the "cash key" of a cash till from being actuated before any 65 of the calculating keys have been actuated, indicating mechanism for showing the amount of a purchase in a cash till, a zeroizing device for returning all the counting drums to zero, indicating mechanism for indicating details upon a strip of paper in addition to indicating the calculations upon 70 the counting drums, and mechanism for rotating the counting drums in one direction or the other for the purpose of enabling the 75 arithmetical processes of multiplication and subtraction to be performed.

In order that the said invention may be clearly understood and readily carried into effect I will describe the same with reference 80 to the accompanying drawings which illustrate the invention as applied to a cash till.

Figure 1, is a horizontal section of a cash till showing more particularly the totalizing and carrying on mechanism and mechanism 90 for actuating the same. Fig. 2, is a sectional side elevation taken approximately on line 2, 2, of Fig. 1. Fig. 3, is a detached view of the carry on mechanism drawn to an enlarged scale. Fig. 4, is a transverse section 95 taken on line 4, 4, of Fig. 3. Fig. 5, is a similar view looking in the opposite direction. Fig. 6, is a section taken approximately on line 6, 6, of Fig. 1, showing the racks together with their operating pinions. Fig. 7, is an end elevation showing the fall stroke mechanism and drawer releasing 100 mechanism. Fig. 8, is a detached view of the drawer releasing mechanism. Fig. 9, is a detached view of the indicating mechanism shown in Fig. 2. Fig. 10, is a detached view of a form of indicating mechanism which may be employed for recording details and totals upon a strip of paper in addition to indicating the calculations upon 105 110

the drum. Fig. 11 is a horizontal section showing a form of mechanism for returning the drums to zero. Fig. 12, is a transverse section taken approximately on line 12, 12, 5 of Fig. 11. Figs. 13, 14 and 15, are detached views of a portion of the zeroizing mechanism. Fig. 16, is a detached view of a modification of the totalizing mechanism adapted to perform the arithmetical processes of 10 multiplication and subtraction. Fig. 17, is a front elevation of a portion of the modified form of the totalizing mechanism. Fig. 18, is a transverse section taken on line 18, 18, 15 of Fig. 17, and Fig. 19, is a similar view taken on line 19, 19, of Fig. 17.

The totalizing mechanism for counting or adding purposes comprising a series of rotatably mounted drums A, A', A², A³, which bear the required indications and correspond 20 in number to the character of the coinage, or of the sums to be added. In the arrangement shown, the drum A represents the pence drum, the drums A', A² the shillings drums, and the drum A³ the pounds drum, 25 but obviously these drums could be arranged to indicate any other coinage by slightly modifying the mechanism by which they are actuated.

B, B', represent two sets of keys of which 30 the set B directly controls the pence drum A and the set B' the shillings drum A', the drums A², A³ receiving their motion from the carry on mechanism appertaining to the drum A'. It is also obvious that any required number of sets of keys could be employed according to the particular coinage or sums to be dealt with. Each of the aforesaid drums is rotatably mounted upon a shaft a that extends across the machine. 40 The first drum A of the series receives its motion from a rack a' that is slidably mounted in guides a² carried by the end frame of the machine, and receives its motion from the keyboard B in the manner hereinafter described. Gearing with the rack a' is a pinion a³ rotatably mounted upon the shaft a. This pinion is rigidly connected to a disk a⁴ in the periphery of which is a depression a⁵. The disk a⁴ carries a spring controlled pawl a⁶ that is adapted to engage with a ratchet wheel a⁷ arranged in rigid connection with the first drum A, the said ratchet wheel being rigidly secured to a toothed wheel a⁸ forming part 50 of the first drum A. Movably mounted upon a shaft a¹⁰ extending across the machine behind the shaft a is a spring controlled lever a¹¹, carrying at its free end a transversely arranged pin a¹² that enters 55 the depression a⁵ in the disk a⁴ as soon as the said disk is returned to its normal position after any of the keys of the set B have been actuated. When the pin is in this position 60 it engages with the teeth of the wheel a⁸ and prevents overrunning of the drum A. The 65

indications upon the drum A are brought into and retained in alinement with those of the succeeding drums after a full stroke has been imparted to any of the operating levers B for changing the position of the drum. 70 In the arrangement shown, this alining operation is effected by means of a spring controlled lever a¹³ movably mounted upon a shaft a¹⁴ extending across the machine, the free end of such lever being suitably shaped to engage with the toothed driving wheel a⁸.

Interposed between any two adjacent drums is the fixed carry on cam C. This cam is shaped in accordance with the amount of movement, that is to be imparted from one drum to the next succeeding drum, and in the example shown, the cam between the first and second drum is so arranged that one complete revolution of the first drum

causes the second drum to advance to a sufficient extent to bring the next succeeding indication thereon into view. For this purpose the cam is made in the form of a disk having a portion of its periphery cut

away as shown at c (Fig. 4), for the reception of the above mentioned movably mounted member. This member as shown

comprises a pin c' projecting from a lever c² that is pivoted to the first drum A, the

said pin being of such a length as to extend across the aforesaid driving wheel c³ of the second drum A'. This driving wheel hereinafter referred to as the "first carry

on-wheel" is fixed to a sleeve projecting

from the second drum. When the first drum has completed a predetermined portion of

its movement, the pin c' on the lever c² enters one of the recesses between the teeth

in the aforesaid carry on wheel and rotates

the second drum A' until the rotation of the first drum causes the pin c' to pass from

the cut away portion in the carry on cam onto the circular peripheral portion thereof

in which position it becomes disengaged with

the carry on wheel c³, and travels around

such peripheral portion without imparting

further motion to the second drum. In

order to insure that the pin c' will follow

the contour of the cut away portion c of the

carry on cam C however quickly the ma-

chine may be operated, a spring controlled

lever c⁴ is pivoted on the shaft a¹⁰ and is

provided at its free end with an extension c⁵

having an inclined portion c⁶ (Fig. 5). This

lever is also provided with a pin c⁷ that

normally rests in a recess a⁸ in a disk a⁴

and engages with the teeth of a wheel a⁸

that is rigidly connected with the second

drum. When the pin c' comes into con-

tact with the inclined portion c⁶, it lifts

the lever c⁴ against the action of its spring

as it passes between the said inclined por-

tion and the cut away portion of the cam.

This movement of the lever also releases

the pin c^9 from the wheel a^8 during the time that the pin c' is actuating the carry on wheel c^8 and allows the latter to be moved through the space of one tooth, whereupon the pin c^9 again engages with the recess a^5 in the disk a^4 and locks the drum A' in position.

In order to retain the indications on the second drum A' in alinement with the indications on the first drum, a spring controlled lever a^{15} is pivoted upon the shaft a^{10} and is suitably shaped at its free end to engage with the teeth of the first carry on wheel c^2 .

The mechanism for imparting motion directly to the second drum A' from the second set of keys B' is practically a repetition of that which has been described with reference to the first drum A , and comprises the rack a' slidably mounted in guides a^2 , the pinion a^2 rotatably mounted upon the shaft a , the recessed disk a^4 that carries the pawl a^6 , and the ratchet wheel a^7 fixed to the ratchet wheel a^8 . This wheel prevents over running of the drum A' by reason of the transverse pin c^9 normally taking up a position between the teeth of the ratchet wheel a^8 , the said pin in this case being arranged to project from one side of the lever c^4 .

The carry on mechanism between the second and third drums A' , A^2 , is the same as that which has been described with reference to the first two drums with the exception that the carry on cam C is so shaped that every complete revolution of the drum A' will impart half a revolution to the drum A^2 . For this purpose two diametrically opposite teeth, c^1 of the second carry on wheel c^2 are arranged to extend from the face of such wheel, and the carry on cam is so shaped that when the parts are in the position shown in Fig. 3, it will allow the pin c' on the pivoted lever c^2 to engage with one of the aforesaid teeth c^1 , and to remain in engagement with such tooth until the second drum has completed half a revolution. The pin c' now travels over a portion of the cam that is of a greater radius and is thereby lifted out of engagement with the tooth c^1 , whereupon the second drum can continue the second half of its revolution without imparting any further motion to the second carry on wheel c^2 until the pin c' comes into contact with the second projecting tooth c^1 and repeats the above mentioned operation, the stop c^4 on the lever c^2 acting in the manner above described with reference to the pin c^9 and also serving to prevent the carry on wheel c^2 from over running. By varying the shape of the carry on cam, any predetermined portion of a revolution can be imparted to the next succeeding drum by one complete revolution of the preceding drum.

The arrangement above described is re-

peated between the third and fourth drums with the exception that the carry on cam C is similarly shaped to the carry on cam shown in Fig. 4, and the two projecting teeth c^1 are not employed on the third carry on wheel c^2 . In each case the motion from one drum to the next succeeding drum is effected by the pin c' on the lever c^2 carried by the preceding drum, the fixed carry on cam C and the carry on wheel c^2 of the succeeding drum, the levers a^{15} affecting the alinement of the indications on the drums, and the levers c^4 insuring the pins c' following the contour of their respective cams and also locking and preventing over running of the carry on wheels.

The two sets of keys, B , B' , hereinbefore referred to comprise a number of levers b each of which is arranged to impart a predetermined amount of movement to its respective drum. Each of the levers is pivoted intermediate of its length to a shaft b^7 extending across the machine, the operating end of each lever being provided with a key b^2 bearing the required indication. Each lever is connected at its opposite end by a pin and slot connection with a rack b^3 that is slidably mounted in guides b^4 , b^5 , extending across the frame of the machine, one set of racks being provided for each set of keys B , B' . Each set of racks is provided with a set of pinions b^6 rigidly fixed upon a shaft b^7 that is supported in bearings b^8 so as to occupy a position adjacent to and in front of its corresponding set of racks. Each set of pinions is provided with a driving pinion or toothed wheel b^9 that gears with the aforesaid slidably mounted driving rack a' . The teeth of each upright rack vary in number according to the amount of movement that they are intended to impart to their respective counting drum, and each such rack together with its operating lever is returned to its normal position after operation, by means of a spring b^{10} connected to each operating lever and to a shaft b^{11} extending across the machine. When the racks are in their normal position the lowermost tooth of each rack rests upon the guide b^5 . In this position the teeth of all the racks are disengaged from their respective pinions and a certain amount of lost motion takes place during the upward travel of each rack before it commences its effective stroke, the said lost motion increasing as the teeth upon each rack decrease in number. By this means each key is compelled to receive the same amount of movement for effecting its full stroke, and in order to give an approximately even touch to all the keys, stronger lifting springs b^{10} are advantageously employed in connection with those racks and levers which have the greater proportion of lost motion.

Any suitable device may be employed for compelling each of the levers to receive a full stroke before it can again return to its normal or top position. A preferred construction of mechanism for effecting this purpose comprises a locking bar G for each set of racks, and means for retaining such bar in spring contact with ratchet teeth g formed on each of the racks b^3 . For effecting this purpose each locking bar G is mounted upon arms g' that project from a sleeve g^2 rotatably mounted upon a shaft g^3 extending across the rear of the machine, any suitable form of springs being employed for causing the bars G to bear against their respective sets of racks. Each locking bar G is provided with a releasing device for temporarily withdrawing the bar out of contact with the ratchet teeth during a portion of the closing movement of the drawer. One form of device for effecting this purpose comprises a cam g^4 carrying an arm a^{19} and pivoted to one end frame of the machine, and a releasing lever g^5 that is also pivoted to the said end frame and is arranged to engage with an arm g^6 projecting from one end of the sleeve g^2 . Upon depressing any one of the keys, its corresponding rack is raised into engagement with its respective pinion, whereupon the set of pinions to which such pinion belongs is rotated through a predetermined portion of a revolution in accordance with the number of teeth upon the aforesaid rack. This movement is transmitted to the driving pinion b^9 which consequently causes the driving rack a' to travel toward the back of the machine in opposition to a pull that is exerted upon such rack by a chain a^{16} and spring a^{17} . This chain is connected at a^{18} to the rack a' and to the aforesaid arm a^{19} through the stud a^{20} . The aforesaid movement of the rack rotates the pinion a^8 together with the recessed disk a^4 and pawl a^5 which travels over the teeth of the ratchet wheel a^7 without imparting any motion thereto. After a complete stroke has been imparted to the aforesaid key, the drawer E of the cash till can be opened in the ordinary manner by depressing the cash key F . The lever f of this key is connected to a spring controlled bell crank lever f' pivoted to the base of the machine at the rear of the drawer E , (Figs. 6 and 7) and when the said key is depressed the vertical arm of the bell crank lever engages with a spring controlled latch f^2 (Fig. 8) and disengages the same from a stud f^3 fixed to the base of the machine, whereupon the drawer opens automatically through the intervention of the spring that is usually employed for effecting such purpose. Upon closing the drawer after it has been opened to its full extent, an arm e that is pivoted at one side thereof engages with the projection a^{20} on the lever a^{19} and turns the latter about its pivot, whereupon the cam g^4 actuates the releasing lever g^5 to temporarily release the locking bar G from the ratchet teeth g . As soon as the locking bar G is released, the continued movement of the lever a^{19} returns the rack a' to its original position through the intervention of the chain a^{16} thereby causing the pawl a^5 to rotate the ratchet wheel a^7 and to transmit such motion to the first drum A . Before the drawer is entirely closed, the pivoted arm e passes under the projection a^{20} on the lever a^{19} whereupon the latter is returned to its original position by the spring a^{17} and the cam g^4 is correspondingly moved and allows the releasing bar G to again engage with the ratchet teeth g on the backs of the racks b^3 . Every time the rack a' returns to its original position, it brings the recess a^5 in the disk a^4 underneath the transverse pin a^{12} which then engages with the teeth of the ratchet wheel a^7 and prevents over running of the latter.

A suitable form of locking device for preventing the cash key F from being depressed and the drawer E opened before any of the keys b have been actuated, comprises a bell crank lever H , (Fig. 6) and a cranked bar, H' that is pivoted to the upper of the shafts b^7 and extends across all of the key levers b . The lever H is pivoted to a portion of the machine frame in front of the racks b^3 and is normally supported in the position shown by a fixed stop h that engages with a horizontal arm of such lever when all the keys are in their normal or uppermost position. When the lever H is in this position, its vertical arm comes directly over the lever f of the cash key F and prevents the latter from being actuated. As soon however as any of the levers b are operated, the cranked bar H' is raised until it comes into contact with the horizontal arm of the lever H and turns the vertical arm thereof out of alignment with the lever f whereupon the cash key can be actuated to open the drawer.

A suitable form of indicating device for showing the amount of the purchase comprises an indicating drum J for each set of keys B B' . Each drum bears the required indications and is rotatably mounted upon a shaft j extending across the top of the machine, any of the said indications being capable of being brought into view in accordance with the amount of the purchase. In the drawings one such drum only is shown together with the mechanism for actuating the same, (Figs. 2 and 9). This mechanism comprises a pinion j' that is rigidly fixed upon the pinion shaft b^1 and gears continually with a slidably mounted rack j^2 supported in the guides b^4 , b^5 . Situated above this rack is another rack j^3 slid-

ably mounted in a guide j^4 , and arranged to gear continually with a pinion j^5 that is fixed to the drum J . Also fixed to such drum is a ratchet wheel j^7 , and pivotally mounted on a shaft j^8 that extends across the rear portion of the machine is a lever j^9 provided at its upper end with a spring controlled pawl j^{10} which allows the ratchet wheel j^7 to be rotated in one direction when the said pawl is in engagement with the wheel. The lower end of this lever extends into proximity to the base of the machine and is adapted to be engaged by a spring j^{11} that is fixed to the back of the drawer D .

When any of the keys b are depressed the amount of motion that is transmitted from such keys to the pinion shaft b^1 raises the racks j^2 j^3 and transmits a corresponding amount of motion to the pinion j^6 with the result that the required indication upon the drum is brought into view. Upon depressing the "cash key" the drawer opens and the lever j^9 assumes a position in which its pawl j^{10} is disengaged with the ratchet wheel j^7 the racks being retained in their raised position through the intervention of the locking bar G . On again closing the drawer, the spring j^{11} actuates the lever j^9 to engage the pawl j^{10} with the ratchet wheel j^7 thereby retaining the indicating drum in its above-mentioned position and the key that has been actuated returns to its normal position together with the rack j^2 . When another key is depressed, if such key is of a lower denomination, a spring j^{12} returns the indicating drum J to a position in which the corresponding lower denomination upon the drum will be brought into view. If a "no sale" key is operated to raise the bar H' and thereby to allow the cash key F to be depressed to open the drawer, the drum J is returned until a stop j^{13} thereon engages with a fixed stop j^{14} in which position a zero indication upon the drum is brought into view. This also happens to the drum appertaining to a set of keys in which no key has been depressed when a key that appertains to another set of keys is depressed. By the arrangement hereinbefore described, any required indication remains in view until a key of a higher or a lower denomination is actuated.

Each of the counting drums A , A' , A^2 and A^3 is provided with a device by means of which all of such drums can be returned to zero when required, and in the arrangement shown in Figs. 11 to 15, the device comprises a releasing bar K that is actuated from a zero key K' occupying a position within the casing of the machine. The releasing bar K extends over the top of each of the above mentioned levers c^4 in proximity to tail pieces k that are formed upon the said levers and is secured at each end to one arm of a bell crank lever k^4 that is suitably pivoted to the machine frame. The other arm of the bell crank lever engages with one arm of a lever k^2 that is also pivoted to the machine frame, the opposite arm of such lever being engaged by a cam k^3 that is formed upon the end of a slotted lever k^4 . This lever is connected by a pin k^5 to a slidably mounted rack k^6 that carries the aforesaid zero key K' . Gearing with the rack k^6 is a pinion k^7 fixed to a clutch member k^8 rotatably mounted upon a shaft k^9 that is slidably and rotatably mounted in suitable bearings in the machine frame. k^{10} represents another clutch member that is rigidly fixed upon the shaft k^9 and is normally retained in engagement with the clutch member k^8 by a spring k^{11} . Fixed upon the shaft k^9 are two pins k^{12} which normally occupy a position out of alignment with the path that is described by two pins k^{13} fixed on two toothed wheels k^{14} that are rotatably mounted upon the shaft k^9 . Each toothed wheel k^{14} gears with a toothed wheel k^{15} that is fixed to its respective counting drum and each wheel k^{14} is retained in alignment with its respective wheel k^{15} by distance pieces k^{16} which are slotted where required for the passage of the pins k^{12} . Each of the above mentioned clutch members is formed with an inclined face as shown in Figs. 11, 13 and 15, and with a projection k^{17} that is adapted to be engaged by a pivoted catch lever k^{18} having a recess k^{19} to receive either of the projections k^{17} . To return the counting drums A , A' , A^2 , A^3 to zero, the zero key K' is depressed to its full extent. This movement imparts one and a half revolutions to the clutch member k^8 . The first half revolution moves the clutch member k^{10} in an endwise direction without rotating such member and causes the two clutch members to assume the position indicated in Fig. 14, with the result that the shaft k^9 is moved in an endwise direction and brings the pins k^{12} into alignment with the path described by the pins k^{13} . Slightly before the projection k^{17} on the clutch member k^8 engages with the corresponding projection on the clutch member k^{10} , the first mentioned projection comes into contact with the inclined end of the catch lever k^{18} and raises the latter clear of the projection on the clutch member k^{10} . The projection on the first clutch member then engages with the projection on the second clutch member and rotates the latter through one complete revolution with the result that the pins k^{12} on the shaft k^9 are brought into alignment with the toothed pins k^{13} on the toothed wheels k^{14} which then return the counting drums to zero. Previous to the effecting of this operation and during the initial movement of the zero key K the cam k^3 on the slotted lever k^4 actuates the releasing bar K to engage with the tail pieces k .

formed upon the levers c^4 and to raise the latter clear of the carry on wheels c^3 and thereby to release the counting drums.

A form of mechanism that may be employed for indicating details upon a strip of paper in addition to indicating the calculations upon the counting drums is illustrated in Fig. 10 and comprises two drums L, L' rotatably mounted upon the shaft a^{14} and arranged directly opposite to the counting drums A, A' . The drum L is actuated from the first rack a' (that imparts motion directly to the drum A) through the intervention of a pinion l that gears with such rack and is fixed upon the end of a sleeve l' connected to the drum L . The drum L' is in like manner actuated by a pinion l^2 gearing with the second rack a' that imparts motion directly to the counting drum A' . The indications on each drum are formed in type and adapted (if required) to be transmitted to a strip of paper by any suitable means, such for example as an ink ribbon traversed between the drums and the paper. Each drum L or L' receives a rotary reciprocating motion from the rack a' during the working and the return stroke of any of the keys b and returns to zero as such key returns to its normal position.

This improved calculating machine is provided with a totalizing mechanism adapted to perform the arithmetical processes of multiplication and subtraction, and this mechanism includes means whereby the counting drums may be rotated in either direction according to requirements. This totalizing mechanism is disclosed in Figs. 16 to 19 inclusive, in which A represents the counting drum to which the mechanism is applied. This drum is rotatably mounted upon the shaft a and is provided with two driving wheels a^3, a^{34} rotatably mounted upon the shaft a . The driving wheel a^3 is rigidly connected to the recessed disk a^4 that carries a spring controlled pawl a^6 adapted to engage with a right hand ratchet wheel a^7 arranged in rigid connection with the drum A , the said ratchet wheel being rigidly secured to the toothed wheel a^8 hereinbefore described. The driving wheel a^{34} is in like manner rigidly secured to a recessed disk a^4 that carries a spring controlled pawl a^{38} adapted to engage with a left hand ratchet wheel a^{74} arranged in rigid connection with the drum A , the said ratchet wheel being also rigidly secured to its adjacent toothed wheel a^8 . Rotatably mounted upon a shaft a^{11} arranged parallel with the shaft a is a pinion a^{22} (hereinafter referred to as the reversing pinion) arranged in line with the driving wheel a^3 and connected to a toothed wheel a^{28} gearing with the other driving wheel a^3 . Either the first mentioned driving wheel a^3 or the reversing pinion a^{22} is adapt-

ed to be engaged by a slidably mounted rack a^{24} which receives its movement from the toothed wheel b^8 hereinbefore referred to, and for effecting this purpose the rack a^{24} is pivotally as well as slidably mounted, one end of the said rack being arranged to slide in a guide a^{25} that is pivotally connected with the lower end of an upright rod a^{26} which is slidably mounted in guides a^{27} and is provided at its upper end with a key a^{28} that projects through the casing of the machine. The rod a^{26} is formed with two recesses a^{29} and a^{30} either of which can be brought into engagement with a portion of the casing to retain such rod in its top or bottom position. When the rack a^{24} is caused to engage directly with the driving wheel a^3 , the drum A is driven in one direction, and when the rack is moved into engagement with the reversing pinion a^{22} the drive is transmitted from the latter through the toothed wheel a^{23} to the other driving wheel a^{34} and the drive is transmitted to the drum A in the reverse direction. a^{31} represents a slidably mounted rack that is driven from the pinion b^8 and gears at its opposite end with the pinion l that drives the indicating drum L above referred to, a portion of the rack being cut away at a^{32} so as not to engage with the pinion a^3 . The carry mechanism for transmitting the motion from one drum to another, and the alining mechanism for retaining each drum in its correct position upon the return of its actuating lever or key to its normal position may be substantially the same as that which has already been described.

What I claim and desire to secure by Letters Patent of the United States is:—

1. In a calculating machine, a set of keys, a rack operable by the keys, a shaft, a pinion loose upon the shaft and meshing with the rack, a disk on the shaft and fixed to the pinion to move therewith, said disk having a peripheral depression at one side, a drum rotatable on the shaft, a ratchet wheel loose on the shaft, a pawl on the disk normally engaging the ratchet wheel, a toothed wheel loose on the shaft having connection with the ratchet wheel to turn therewith, a second shaft, a normally depressed lever hinged on the second shaft, a laterally extending pin on the lever adapted to engage in the peripheral depression of said disk and with the teeth of said toothed wheel to lock said drum from turning, a third shaft, a spring pressed lever on the third shaft engaging said toothed wheel.

2. The combination with a cash till provided with sets of operating keys, of a locking bar a series of racks each of which is operatively connected with its respective key lever and is provided with a number of ratchet teeth arranged to be engaged by the locking bar, said locking bar being capable

- of being automatically withdrawn from the teeth when required, a series of pinions rotated by such racks, a spring controlled indicating drum for each set of keys, a rack 5 gearing with one of said pinions and operatively connected with its respective indicating drum, a pinion rigidly connected with each indicating drum, a rack gearing with such pinion and arranged to receive 10 motion from the first mentioned rack, a ratchet wheel rigidly secured to each indicating drum, a drawer in said cash till normally urged into open position, a pivoted lever provided with a pawl that occupies a position away from such ratchet wheel when the drawer of the cash till is open and means for bringing such pawl into engagement with the ratchet wheel when the drawer of the cash till is closed and for retaining such wheel in position until the locking bar is released from the ratchet teeth formed on the racks that are actuated by the depression of any of the operating 20 keys.
- 25 3. In a machine of the character described, a reciprocating rack, keys associated with the rack for moving the same, a pinion meshing with the rack, a disk rigid at one side of the pinion and having its edge 30 flush with the outer edges of the teeth of the pinion, the disk further having at one side a notch in its edge of a depth corresponding to the throat of the adjacent teeth, a counting drum, a ratchet wheel fixed to 35 the counting drum concentric to the pinion, a spring pressed pawl carried by the pinion and engaging the ratchet wheel, a spring controlled lever, a transversely extending
- pin on the outer end of the lever being normally urged by the latter against the edges 40 of the disk, and means controllable by the keys engaging the lever to raise the same from the disk and release the same upon a predetermined movement of the pinion.
4. In a calculating machine, sets of operating keys, racks connected to the keys to be reciprocated thereby, a locking bar adapted for engagement with the teeth of the racks, said bar also being adapted for automatic releasing from said teeth, a set of pinions 50 meshing with the racks, a spring controlled indicating drum for each set of keys, drum-operating racks connected to the drums and meshing with a respective pinion in each of the said sets of pinions, a drum-pinion 55 rigidly connected to each indicating drum, a drum-rack meshing with each of the drum-pinions and adapted to receive motion from said first racks, a ratchet wheel rigid with each indicating drum, a drawer in the machine normally urged into open position, a pivoted cash lever, a pawl on the lever normally held from said ratchet wheels by said drawer when open, and means associated with the pawl for releasing the same when said drawer is closed whereby the pawl engages the ratchet wheels and holds the same from movement until the locking bar releases said first racks.

In testimony whereof I affix my signature, 70
in presence of two witnesses.

ARTHUR JOHN HERBERT BURNETT.
